UNITED STATES PATENT OFFICE.

EDWARD J. MITCHELSON, OF SAYBROOK, OHIO.

SAP-FEEDER.

SPECIFICATION forming part of Letters Patent No. 290,910, dated December 25, 1883.

Application filed May 24, 1883. (No model.)

To all whom it may concern:

Be it known that I, EDWARD J. MITCHELSON, a citizen of the United States, residing at Saybrook, in the county of Ashtabula and State 5 of Ohio, have invented certain new and useful Improvements in Sap-Feeders; and I do declare the following to be a full, clear, and exact description of the invention, such as will enable others skilled in the art to which it applies 10 pertains to make and use the same, reference being had to the accompanying drawings, and to the letters and figures of reference marked thereon, which form a part of this specification.

This invention relates to improvements in 15 evaporators used in the manufacture of sugar; and it consists of the combination and arrangement of parts, substantially as hereinafter fully set forth and claimed.

In the accompanying drawings, Figure 1 is 20 a side view of my improved evaporator. Fig. 2 is a vertical sectional elevation thereof, and Fig. 3 is a detail side view of the same.

In carrying my invention into effect, I employ a pan, A, preferably rectangular and superposed upon a furnace, B, the chimney *a* of 25 which is connected thereto by a narrow passage or flue, *a'*.

Between the pan and chimney, and with its bottom forming the top of this passage, is arranged 30 a small tank or superheater, C, which is supported upon an extension of the masonry of the furnace by deflected metal plates *b*, secured to the sides of the said tank.

c is a tube or flue leading from the furnace 35 through the tank C to and communicating with the chimney. A valve or perforated slide, *d*, adapted to be operated from the outside by a suitable handle projecting therefrom, is disposed to slide over the furnace end of the 40 tubular flue *c*, to cutoff or permit the passage of heat through the latter, as may be desired. The tank and pan-chambers are connected by an overflow aperture or pipe, *e*.

D is the supply-tank containing the sirup 45 or substance for conversion into sugar, and which is supported in an elevated position in any suitable manner.

E is the supply-pipe conducting the sirup or material from the tank D to the tank or superheater C, and which is provided with a cock 50

and with a valve, F, adapted to open and close the passage of pipe E, for which purpose the said valve is connected by the jointed connection *fg* to one end of the centrally-pivoted lever G, the other end of said lever having a 55 float, H, attached thereto by a rod, *h*, adapted to rise and fall with the liquid in the pan A. The lever G is pivoted upon the upright G', suitably secured in place. A pipe, I, leads from the top of the cover A' of the pan A to 60 the chimney *a*, to allow the passing off of the steam from the contents of the pan.

In operation the liquid or sirup which is supplied to the tank C, and partially heated therein, as it continues to flow or rise, will 65 overflow through the aperture or pipe *e* and pass into the pan A, where it is evaporated, its precipitate being converted into sugar. As the liquid rises in the pan A, the float H will be proportionally lifted therewith and cause 70 the closing of the valve F, which will stop the flow of the liquid through the pipe E. As the process of evaporation takes place, the liquid will of course descend, which will cause the descent of the float H therein, and consequently 75 reverse the movement of the valve and cause the flow of the liquid again.

Having thus fully described my invention, I claim and desire to secure by Letters Patent—

1. In an evaporator, the combination, with 80 the evaporating-pan superposed upon the furnace and the flue or chimney *a*, of the superheater or tank and the flue-tube passed through the latter, and having means to cutoff the passage or supply thereto, substantially as and 85 for the purpose set forth.

2. In an evaporator, the combination, with 90 the pan, the superheater or tank, an overflow-passage connecting the chambers of the same and the supply-tank, of the supply-pipe and its valve, the jointed connection, the lever and float connected to the latter, substantially as and for the purpose set forth.

In testimony whereof I affix my signature in presence of two witnesses.

EDWARD J. MITCHELSON.
